UNITED STATES PATENT OFFICE.

JOHN A. JOHNSON, OF MANFRED, NORTH DAKOTA.

COLLAPSIBLE GRAIN-CLEANING DEVICE.

1,242,811.

Specification of Letters Patent. Patented Oct. 9, 1917.

Application filed January 31, 1917. Serial No. 145,677.

To all whom it may concern:

Be it known that I, JOHN A. JOHNSON, a citizen of the United States, residing at Manfred, in the county of Wells and State 5 of North Dakota, have invented certain new and useful Improvements in Collapsible Grain-Cleaning Devices; and I do hereby declare the following to be a full, clear, and exact description of the invention, such 10 as will enable others skilled in the art to which it appertains to make and use the same.

This invention relates to a grain cleaning device and has for its primary object to 15 provide a device of this character whereby wheat, barley, oats and other similar grains may be readily cleaned and at the same time serving to remove any wild grain, such as wild oats from the good grain.

Another object of the invention is to provide a device of this character which can 20 be quickly and readily collapsed and packed in such a manner as to occupy a minimum amount of space.

Another object of the invention is to provide a frame work designed to support an endless apron at an inclination, and a feed hopper disposed above the apron, means being provided for rotating the apron beneath the hopper, the good grain gravitating 25 down the apron, while the wild grain or other foreign substance adheres to the apron and is carried upwardly and over the end of the same to a position in the rear where means is provided for scraping the wild grain beards and other foreign matter from the apron.

A further object of the invention is to provide a fleeced endless apron to which the 30 wild beards of the grain or other foreign matter is designed to adhere and subsequently be scraped off.

A still further object of the invention is to pivotally support the upper end of the 35 apron beneath the hopper and to provide means for vertically adjusting the lower end of the apron to vary the angular inclination of the apron with respect to the hopper for use in connection with different kinds of grain.

With these and other objects in view as will appear as the description proceeds, the invention comprises the various novel fea-

tures of construction, combination and arrangement of parts, as will be more fully 55 described hereinafter and set forth with particularity in the appended claim.

Referring to the drawings,

Figure 1 is a perspective view of my novel grain cleaning device. 60

Fig. 2 is a vertical longitudinal sectional view through the device.

Similar characters of reference are used to denote like parts throughout the accompanying drawings and the following description. 65

Referring more particularly to the drawings, my improved grain cleaning device is shown to consist of a pair of substantially triangular supporting frames A, each of 70 which consists of a vertically disposed supporting leg 1 which has attached to its upper end a hinge member 2 that is provided with a forward and lateral extension 3. Pivotally attached to this lateral projection 3 is the upper end of a downwardly and forwardly inclined supporting leg 4, the lower end of which is held in spaced 75 relation to the leg 1 through the medium of a brace arm 5 that is pivotally connected 80 as at 6 to the supporting leg 1 and has its opposite end engaged over a lateral projection 7 carried by the leg 4.

Disposed between the triangular frames A is an apron frame B which consists of a 85 pair of spaced side bars 8 that are connected by a platform 9 that is supported at its opposite sides by the cross bars or strips 10 and is securely attached at its opposite sides to the side bars 8. As shown the platform 9 has its upper and lower ends terminating at points adjacent to the opposite ends of the side bars. 90

Journaled in the opposite ends of each of the side bars 8 are rollers 11 and 12 respectively, the roller 11 being provided with trunnions 13 that are slidably and adjustably mounted in slots 14 extending transversely through the lower ends of the side bars 8. 95

The trunnions 15 of the roller 12 extend through the upper ends of the side bars 8 and through the upper ends of the supporting legs 4, the latter forming a suitable support for the apron frame. 100

Fixed upon the outer end of one of these

trunnions 15 is a sprocket wheel 16 around which is trained a sprocket chain 17, and which is connected to and trained around a sprocket wheel 18 mounted upon a stub shaft 19 that is journaled in the supporting leg 4 at a suitable distance below the upper sprocket wheel 16. This lower sprocket wheel 18 is designed to be positioned within easy reach of the operator and connected to this stub shaft 19 of the sprocket is a crank handle 20 by the rotation of which the upper roller 12 may be revolved.

Extending around the rollers 11 and 12 is an endless fleeced apron 21 and by the means for adjusting the lower roller 11, it will be apparent that any desired amount of tension can be placed upon this apron so as to make it most effective in its operation. While it is desired to have the outer surface of the apron fleeced, it is to be understood that this apron may be constructed of any such material as canton flannel or any other material having a nap of the desired length which will be most effective in the operation of the device.

The lower end of the apron frame B is designed to be supported through the medium of a pair of supporting legs 22, each of which is pivotally attached at its upper end as at 23 to the lower end of the side bar 8, while the outer end of each supporting leg is provided with a sharpened pin 23' designed to engage the floor or surface upon which the device is mounted to hold the lower end of the apron frame in any desired adjusted position.

A grain hopper 24, which in this instance is shown to be of substantially triangular relation in cross section, is adjustably supported above the upper end of the apron frame. The opposite rear ends 25 of the hopper are pivotally and detachably supported as at 26 between the supporting brackets 27.

The opposite forward end portions of the hopper are supported through the medium of supporting legs 28, each of which has its upper end pivotally attached as at 29 to the end of the hopper and its opposite end frictionally resting upon the upper surface of the supporting leg 4, and its lower end, if desired, may be supported in a notch 30 formed in the supporting leg 4. The lower portion of the hopper is provided throughout its length with a longitudinally extending slot 31 through which the grain is adapted to be discharged on to the endless apron 21.

In the operation of the device the grain to be cleaned, and we will say for instance it is desired to clean wheat, is placed in the hopper and the endless apron rotated in the direction of the arrow whereby the wheat as it is discharged from the hopper on to

the apron will gravitate or roll downwardly over the apron and subsequently on to the floor, while all beards or other foreign matter that may be mixed with the wheat will adhere to the fleece or nap of the apron and be carried over and around to the rear of the apron frame, where it will be scraped off through the medium of a scraper bar 32 that extends transversely across and is connected to the side bars 8. This scraper bar 75 has its opposite edges sharpened as at 33 and rests against the underneath surface of the other apron so as to effectively scrape the beards or foreign particles from the apron as it is rotated.

While it is preferably desired to rotate the apron in the direction indicated by the arrow it is to be understood that the same may be operated in a reverse direction and still clean the grain but not quite as effectively as if rotated as described, and in order to provide for this I have sharpened both edges of the scraper blade 32.

While I have shown a single strip of metal used as a scraper blade, I desire to have it understood that a plurality of wires may be stretched across the apron and connected to the side bars and will effectively serve the same purpose as the scraper blade 32.

For instance if it is desired to clean oats or barley, the lower end of the apron frame B will be lowered so that the barley or oats which is of a different character and shape from the wheat will roll or gravitate more readily and freely down the apron. In view of the fact that the wheat grains are more rounded than the oat or barley grains it will be apparent that they will more readily roll down the apron when disposed at a less inclination than would the oat or barley grains. Therefore, to provide for an equal gravitation of various kinds of grain, adjusting means is provided for the lower end of the apron frame.

From the construction of the device shown and described, it will be apparent that the device can be readily collapsed or disassembled and packed together in a compact bundle so as to occupy a minimum amount of space when there is no further use for the device.

What I claim is:

A knock down grain cleaning device comprising a pair of main supporting frames, 120 each frame consisting of inclined supporting legs connected together at their upper ends, a hopper pivotally mounted at its ends and at one side to the upper ends of said inclined legs, a supporting leg pivotally connected at its upper end to each end of the hopper and to the side opposite the pivotal connections of said hopper and adapted to be supported at its lower end on the adjacent inclined supporting leg, a separator 125

member pivoted at its upper end to said inclined supporting legs at points between the pivotal connections of the hopper and the lower ends of the hopper supporting legs 5 with said inclined legs, and means for adjustably supporting the lower end of said separator member.

In testimony whereof I have signed my name to this specification in the presence of two subscribing witnesses.

JOHN A. JOHNSON.
